UNITED STATES PATENT OFFICE.

ROSS J. VOSBURGH, OF BROOKLYN, NEW YORK, ASSIGNOR, BY MESNE ASSIGNMENTS,
TO SAMUEL M. KINTNER, OF PITTSBURGH, PENNSYLVANIA, AND HALSEY M.
BARRETT, OF BLOOMFIELD, NEW JERSEY, RECEIVERS.

WIRELESS-TELEGRAPH DETECTOR.

1,182,946.

Specification of Letters Patent. Patented May 16, 1916.

Application filed August 29, 1913. Serial No. 787,298.

To all whom it may concern:

Be it known that I, Ross J. VOSBURGH, a citizen of the United States, residing at Brooklyn, in the State of New York, have 5 invented or discovered certain new and useful Improvements in Wireless-Telegraph Detectors, of which the following is a specification.

My invention relates to the class of so-called detectors of electromagnetic wave energy which are direct translators of such energy, consisting of electrodes having the property of changing oscillating current energy into a series of uni-directional dominant pulses.

The object of the invention is to provide such a translating device in a form not disturbed by minute lightning discharges or static disturbances; to avoid the necessity 20 of continual adjustment and preserve a uniform adjustment; to provide for such a firm and unvariable contact between the electrodes as to obviate danger of becoming inoperative from mechanical vibrations, etc.; 25 and to generally improve the construction of mountings for such good contact devices.

I have illustrated the invention in one form in the accompanying drawing which shows in Figure 1 a vertical central section 30 through the detector and in Fig. 2 a diagram of a circuit convenient for using the detector.

Wireless telegraph detectors generally are divided into imperfect contact devices which 35 are trigger tripping devices to set off a local battery current, and good contact devices which are direct translators of received energy and do not depend upon any change of condition at the contact. My device is 40 one in which there is not only no variation of resistance but in which there is no such contact as could be varied, but a perfectly firm and stable joint between two materials which I have discovered to have the desired 45 property to a very marked degree and with a perfect contact. The intimate operation or electrical phenomena of such devices are not understood, but it is known that oscillating current passing through certain substances, or the contact of certain substances 50 with other substances, has the effect of directly or indirectly transforming the energy

of the oscillating current into what amounts to virtually a uni-directional current capable of operating a telephone or the like. I have 55 discovered that there is a peculiar efficiency in the combination of the minerals carborundum and ferro-silicon, which is more sensitive than either one of these materials alone and is plainly due to the combination, 60 and incidentally has the advantage that they are both capable of withstanding heavy pressure without crushing. Other combinations have the advantage of sensitiveness without the ability to withstand heavy 65 pressure; for example, ferro-silicon and antimony are very sensitive, but cannot withstand heavy pressure on account of the antimony being soft, and similarly carborundum with iron pyrites which is very 70 sensitive but will not withstand sufficiently heavy pressure over a large area of contact to resist static disturbances as well.

In Fig. 1 of the drawing I mount a block of ferro-silicon D in a bedding of Wood's 75 metal I in a metal cup E surrounded by insulation F and in contact through its shank E' with a spring L connected in circuit. The other electrode is the block of carborundum D' embedded in Wood's metal K 80 in the hood H which is threaded to receive the screw ring G supporting the cup E and also threaded on the outside to go in the socket M mounted on the insulated base N and connected to the other lead of the circuit. 85 It is preferable to build the units composed of the two telescoping cups in the laboratory, and after finding the most sensitive spot on the carborundum crystal the ring G is screwed down tight so that the 90 contact is under firm and heavy pressure whereupon the cup H is preferably sealed by a paper wafer to be disturbed no more and then the cup H is inserted in the holder M. This avoids the necessity and risk of 95 operators undertaking to adjust the device and secures uniformity with a large number of such detectors.

I have shown in Fig. 2 a diagram representing an antenna A, a variable inductance 100 P and ground G inductively connected to a local circuit containing the condensers C, C', detector D and telephone indicator T. When extreme sensitiveness is desired I

preferably insert a battery B in one of the leads from the telephone and it is partly to prevent this current flowing through the oscillating circuit that I use the extra condenser C'.

I have made long and severe use of this combination of carborundum and ferro-silicon and find that it is nearly as sensitive as the well known Fessenden liquid barretter, especially when sensitized by using a small battery current through it, and that notwithstanding this sensitiveness it has such stability that it may without injury be dropped on the floor or knocked with a hammer, and holds its adjustment through static disturbances which are severe enough to spark across the protective gap ordinarily used to prevent destruction of such detectors. The efficiency is plainly due to the conjoint properties of the two materials and not to any property of either one alone. I have found several equivalents of this pair of elements, among which are ferro-silicon with antimony and carborundum with iron pyrites. The presence of iron in the combination appears to be important, though I believe it is not now known whether or not ferro-silicon is a chemical compound or

whether or not carborundum is a chemical compound.

Having thus described my invention, what I claim is the following:

1. A translating device for wireless telegraph receivers comprising electrodes of carborundum and ferro-silicon, held under good and stable contact.

2. A translating device for wireless telegraph receivers comprising telescoping screw cups containing respectively ferro-silicon and carborundum in firm and stable contact with each other, and a base or holder having electrical connections and threaded to receive one of the cups and provided with a yielding contact for the other.

3. A wireless telegraph detector comprising a translating element composed of the two minerals ferro-silicon and carborundum permanently held together under heavy pressure and entirely inclosed.

In testimony whereof I have hereunto signed my name in the presence of the two subscribed witnesses.

ROSS J. VOSBURGH.
